UNITED STATES PATENT OFFICE.

JAMES F. McELROY, OF ALBANY, NEW YORK, ASSIGNOR TO CONSOLIDATED CAR-HEATING COMPANY, A CORPORATION OF WEST VIRGINIA.

DOOR-MOTOR CONTROLLER.

1,168,406.

Specification of Letters Patent.

Patented Jan. 18, 1916.

Application filed June 29, 1912. Serial No. 706,781.

To all whom it may concern:

Be it known that I, JAMES F. McELROY, a citizen of the United States, residing at Albany, county of Albany, State of New York, have invented certain new and useful Improvements in Door-Motor Controllers, the following being a full, clear, and exact disclosure of the one form of my invention which I at present deem preferable.

10 For a detailed description of the present form of my invention, reference may be had to the following specification and to the accompanying drawings, which illustrate my invention, wherein—

15 Figure 1 shows my apparatus diagrammatically; Figs. 2 and 3 show in plan view the motor switch; Figs. 4 and 5 show the manual controlling switch, and Fig. 6 a perspective view of the motor switch.

20 My invention relates to the control of a motor, such as a door motor, by means of electromagnetic devices and, in general, I provide that the manual switch which serves as the immediate controlling agency shall be retained in either of its extreme positions by means of an electromagnet, the circuit of which is controlled by the movement of the motor itself. By this means the initial movement of the controlling switch to one position or the other will insure the continued operation of the motor through its entire range of movement, at the end of which movement it automatically releases the manual switch and the consequent return of that switch to its neutral position will automatically release the air pressure on the motor, so that in neither one of its extreme positions will the motor receive the continued presence of the air pressure.

40 Turning to Fig. 1, A represents the motor and D the door operated thereby. This motor is of a construction which is now well known, being shown in my Patent No. 1,002,596, dated September 5, 1911, and it includes two oppositely placed air cylinders, 1 and 2, which act oppositely upon two connected crossheads 3 and 4 which are connected to door D by means of a link 5. There are also two parallel cylinders 6 and 7, the former of which is a dash-pot cylinder for power cylinder 2 and the latter a similar cylinder for power cylinder 1. The admission of air to the right hand end of cylinder 1 will move the connected cross heads to the left to open the door D, as shown in Fig. 1,

wherein the door is represented in its open position, while the admission of air to the left hand end of cylinder 2 will move the cross heads and door to the right to close the door, it being understood that in each case the cylinder which is not acting has its exhaust port open. Each of these cylinders is controlled by means of an electromagnetic valve, the valve for cylinder 1 being shown at B¹ and that for cylinder 2 at B², while the magnets which operate the respective valves are shown at C¹ and C². These magnets C¹ and C² are duplicates of each other, as are also the valves B¹ and B² and the detailed showing of one may be taken as identical with that of the other. Referring particularly to valve B² and its magnet C², the energizing of the magnet will force down a rod 32 passing through the magnet core 33, which rod embraces the end of the stem of puppet valve 26, which is the admission valve, and acts to depress that valve against the force of its seating spring 22, thereby opening the admission port and allowing air to flow from supply pipe 13 through branch 14 and through the admission port which has thus been opened into pipe 12, which leads to the rear end of cylinder 2. At the same time the lower end of the aforesaid rod 32 acts as a valve and closes the outlet port leading to exhaust duct 27. The deenergizing of the magnet produces the reverse conditions, shutting the admission port and opening the exhaust port. The valve B¹ is worked in the same manner by magnet C¹. Each magnet has its coil 34 pocketed between core 33 and the magnet shell 30, said shell being surmounted by a screw cap 35 within which is the armature disk 36 that bridges from core to shell, but is normally held away therefrom by spring 37.

E¹ and E² are two switches placed at separate points of control, such as the two ends of a car, assuming the door D to be a car door. By means of either of these switches either of the magnets C¹ or C² may be either energized or deenergized. Each switch contains a lever 41 pivoted to a plate 40 on the base of the switch. The lever at its pivotal point is embraced between two pivoted arms 42 and 43 which are drawn together by a spring which connects their outer extremities. These levers 42 and 43 thus serve to center the lever 41 and bring it back to its central position after it has

been moved to one side or the other. On the under side of lever 41 is secured a fin-like contact plate 44 of magnetic material which, when the lever is moved to one side or the other comes into engagement with the poles of one of the electromagnets 45 or 46, which poles also serve as contact terminals for the wires 60 and 61. The contact of the plate 44 with the said magnet poles therefore serves to close the electric circuit from the battery F and the plate 40 to either the wire 60 or the wire 61, and thereby energize the magnet 46 or the magnet 45, as the case may be, which thereupon attracts the magnetic plate 44 and retains the lever 41 in whichever of the two extreme positions it has been set. The wire 61 leads to the magnet C² and thence to the contact 70 of the motor switch. The motor switch is shown on an enlarged scale in Figs. 2 and 6, it being understood that its purpose is to automatically break the circuit, which has been closed as aforesaid by the switch E², when the motor reaches the limit of its travel. The switch lever coöperating with the aforesaid contact 70 is shown at 74 in Figs. 2 and 6 and the circuit from contact 70, to which it has been heretofore traced, will proceed by the said switch lever 74 to the retracting spring 75, to switch lever 71, to the block 72, to the wire 73 which leads to the opposite side of the battery F. Closure of this circuit will cause magnet C² to operate and admit air through pipe 12 to the cylinder 2, which, as aforesaid, will cause the movement of the connected cross heads 3 and 4 toward the right to close the door. The cross head 4 carries a pin 50 (see Figs. 2 and 3) which, when the cross head reaches the limit of its travel, will impinge upon the aforesaid switch lever 74 and force it away from the contact 70 and break the circuit which I have above described. That will release switch lever 41 and allow it to come back to its central position by the pressure of arm 42. It will also de-energize magnet C² which will thereupon allow the admission valve to close and the exhaust valve to open which releases the pressure while the door stands in the closed position to which it has been moved. In like manner, when the lever 41 of switch E² is moved to the right, it will bring the plate 44 into contact with the poles of the magnet 46 and thereby close the circuit to the wire 60 from battery F and the plate 40. This will energize the magnet 46 and also the valve magnet C¹ which, like the magnet C², is controlled by the motor switch. The contact of this motor switch to which the wire from magnet C¹ is connected is marked 76, in Figs. 2 and 6, and the switch lever which coöperates therewith is shown at 71. The switch lever 71 is shown in its open position, being engaged by the pin 80 on cross head 3, which corresponds to pin 50 on cross head 4,

it being assumed that this cross head is in its extreme door-opening position, as shown in Fig. 1. The switch E¹ is a duplicate of switch E² and will, in like manner, serve to close the circuit of magnet C¹ or magnet C², according as its lever 41 is moved to the right or to the left. In both cases it will be apparent that when the door motor reaches either limit of its travel it will automatically open the circuit which, by its closure, has initiated the motor action and that this breaking of the circuit will also release the switch lever, which has closed the circuit and which at the same time has been retained in its circuit-closing position by the magnet 45 or 46.

It will be understood that by a door motor I intend to include motors of the same type which have a prescribed range of action.

A conspicuous advantage of my arrangement is that the motorman or guard who operates the door needs only to move the switch and let go of it without waiting and holding it till the door is closed, or watching to see that after the door closes the switch handle is brought back to its central position.

What I claim as new and desire to secure by Letters Patent is:

1. The combination with a reciprocating door motor and a plurality of valves controlling the operation of said motor, of a controller for said valves, electromagnetic means for attracting said controller to maintain the same in operating position, means controlled by the progress of the door for controlling the circuit to said electromagnetic means, and means for normally maintaining said controller in inoperative position. 95

2. The combination with a reciprocating door motor and a plurality of valves controlling the operation of said motor, of a controller for said valves, electromagnetic means for attracting said controller to maintain the same in either of two operating positions, means operated by the motor at or near each end of its range of movement for controlling the circuit to said electro-magnetic means, and means for normally maintaining said controller in inoperative position. 100

3. The combination with a door motor, of valves controlling the direction of movement thereof, electromagnets for operating said valves, a controller for said valves, electro-magnetic means for attracting said controller to maintain the same in operating position, means for normally maintaining said controller in inoperative position, and contact devices in the circuit of said electro-magnetic means, said contact devices being operated by the door motor. 115

4. The combination with a door motor, of valves controlling the direction of movement 120

- thereof, electromagnets for operating said valves, a controller for said valves, spaced apart retaining magnets for attracting said controller to maintain the same in operating 5 position, means for normally maintaining said controller in inoperative position, and circuit breakers in the circuits of said retaining magnets operated by the motor at or near the ends of its range of movement.
- 10 5. The combination with a reciprocating door motor having admission and exhaust ports for both directions of movement, of electro-magnetic valves controlling said ports, a controller for selectively closing the 15 circuits to said magnets, magnetic retaining means for attracting said controller to maintain the same in operating position, means for normally maintaining said controller in inoperative position, and circuit controlling 20 devices in the circuits of said retaining means, operated by the motor at or near each end of its range of movement.
6. The combination with a pressure door motor, of electro-magnetic valves controlling the same, a controller for said valves, spaced apart electromagnets in the same circuit with the valves for attracting said controller to maintain the same in operating position, means for normally maintaining said 25 controller in inoperative position, and circuit controlling devices in the said circuits operated by the motor.
7. The combination with a double acting pressure door motor having separate admission and exhaust ports for each direction of movement, valves controlling the admission and exhaust ports, a separate electromagnet for each set of valves controlling the respective sets of ports, a controller for said magnets, electro-magnetic means for attracting said controller to maintain the same in operating position, means for normally maintaining the controller in inoperative position, and means operated by the motor for 30 breaking the circuit to said electro-magnetic controller-retaining means.
8. The combination with a pressure door motor, of two controlling valves therefor, two electro-magnets in separate circuits for 35 operating the respective valves, a single controller for both of said magnetic circuits, normally stationary contact members in the respective circuits having means for normally maintaining closed circuits to said 40 electromagnets, and means connected with a movable part of the motor to impart movement to one or the other of said contact devices as the motor reaches the end of each stroke, to break the circuit.
- 45 9. The combination with a pressure door motor, of two controlling valves therefor, two electro-magnets in separate circuits for 45
- operating the respective valves, a single controller for both of said magnetic circuits, normally stationary contact members in the respective circuits having means for normally maintaining closed circuits to said 50 electromagnets, means connected with a movable part of the motor to impart movement to one or the other of said contact devices as the motor reaches the end of each stroke, to break the circuit, a controller for said electromagnets, means for retaining said controller in operative position when moved to close the circuit to either of said magnets, 55 and means for normally holding said controller in inoperative position.
10. The combination with a pressure door motor, of two controlling valves therefor, two electro-magnets in separate circuits for 60 operating the respective valves, a single controller for both of said magnetic circuits, normally stationary contact members in the respective circuits having means for normally maintaining closed circuits to said 65 electromagnets, and means connected with a movable part of the motor to impart movement to one or the other of said contact devices as the motor reaches the end of each stroke, to break the circuit, a controller for said 70 electromagnets, retaining magnets for attracting said controller to maintain the same in either of the two valve magnet circuits, said retaining magnets being also included in the valve magnet circuits.
11. The combination with a door motor, of two controlling switches therefor, two valve magnets either of which may be energized or deenergized by either of said controlling switches, and electro-magnet means 75 controlled by the action of a motor, for attracting said switches to maintain them in operative position.
12. The combination with a double acting door motor having two cylinders for the respective movements, of a supply pipe, branches from said pipe leading to the respective cylinders, each branch being provided with admission and control valves, electromagnets for operating the respective 80 valves, a switch for the said magnets, electromagnetic devices for attracting said switch to maintain the same in operative position, and a circuit controller for the valve magnets and the retaining means, 85 operated by the motor.
- In witness whereof I have hereunto set my hand, before two subscribing witnesses, this 27th day of June, 1912.
